DESIGN FOR A TUMBLER OR SIMILAR ARTICLE

Edgar Mott Bottome, Moundsville, W. Va., assignor to Fostoria Glass Company, Moundsville, W. Va., a corporation of West Virginia

Application June 19, 1933. Serial No. 48,444

Term of patent 7 years

To all whom it may concern:

Be it known that I, EDGAR MOTT BOTTOME, a citizen of the United States of America, and resident of Moundsville, county of Marshall, and State of West Virginia, have invented a new, original, and ornamental Design for a Tumbler or Similar Article, of which the following is a specification, reference being had to the accompanying drawing, in which—

The dominant feature of the invention resides in the base having a series of panels the lower edges of which are convex and free while the up-

per portion of the base is surmounted by a pair of superimposed circular beads each of which has a rounded periphery and the upper of which beads is of less diameter than the lower bead, and has a flat top from which the bottom of the bowl of the tumbler emerges.

The single figure is a perspective view of a tumbler or similar article, showing my new design.

I claim—

The ornamental design for a tumbler or similar article, substantially as shown.

EDGAR MOTT BOTTOME.
